UNITED STATES PATENT OFFICE.

CARL E. BAILEY, OF MANCHESTER, NEW HAMPSHIRE, ASSIGNOR TO DRAPER COMPANY, OF HOPEDALE, MASSACHUSETTS, A CORPORATION OF MAINE.

BEAM-LOCK FOR LOOMS.

1,077,385.

Specification of Letters Patent.

Patented Nov. 4, 1913.

Application filed December 9, 1912. Serial No. 735,624.

To all whom it may concern:

Be it known that I, CARL E. BAILEY, a citizen of the United States, and resident of Manchester, county of Hillsboro, State of New Hampshire, have invented an Improvement in Beam-Locks for Looms, of which the following description, in connection with the accompanying drawing, is a specification, like characters on the drawing representing like parts.

This invention relates to looms for weaving, and it has for its particular object to provide a simple, readily operated and efficient locking device for the warp beam, whereby the latter is prevented from jumping or vibrating unduly, and injury to the teeth of the beam gear is obviated.

The lock is so constructed and arranged that it can be rendered inoperative quickly and easily when the beam is to be removed, and said lock can be brought into operative condition as easily and quickly when a new beam has been put in place.

The various novel features of the invention will be fully described in the subjoined specification and particularly pointed out in the following claims.

Figure 1 is a side elevation of a portion of a loom with one embodiment of my present invention applied thereto, the beam lock being shown in locking position by full lines, and by dotted lines in unlocking position ready to release the beam; Fig. 2 is a rear elevation of the loom side, one end of the beam and its journal, and the beam lock, viewing Fig. 1 from the right hand.

The warp-beam B having an attached ring-gear B' and a journal B² at each end, the loom-side A, the whip-roll W, Fig. 1, over which the sheet of warp passes from the beam, and the offset A' at the rear end of each loom-side, are and may be all of usual and well known construction, the offset providing a jog or shoulder at the end of the loom-side.

It is customary to provide each offset with an open bearing A² at its top, in which one of the beam journals is seated rotatably, and a second deeper and inclined bearing A³ is usually provided at the angle formed by the top of the offset, for beams of smaller diameter, the latter bearing, while open, being so shaped that the journal is held therein without much trouble from jumping or undue

vibration of the beam. When the larger beams are used, however, the open bearings A² must be employed, and if nothing but the weight of the beam is depended upon to keep its journals seated the pull of the warp tends to make the beam jump or vibrate improperly, this action tending to irregular let-off and causing rapid wear and injury to the teeth of the ring gear B', which latter meshes with the gearing of the let-off mechanism, not herein shown as it forms no part of my invention.

I have, in accordance with my present invention, provided a simple and effective beam lock for use in keeping the beam journals seated properly in the open bearings A² at the top of the offset of each loom-side, and it will be understood that one of the locking devices is used for each of the beam journals, and as the said devices are precisely alike only one of them is shown and will be described.

It is customary to provide a rigid, temporary support for the beam when putting it into place or removing it from the loom, such support comprising a bracket C having an open journal-seat C', Fig. 1, the bracket being made as a casting with a clamp member C² integral therewith, the other clamp member C³ being bolted to the bracket by a bolt C⁴, and as shown the two clamp members are caused to embrace tightly the upright flange A² of the offset A'.

In accordance with my invention the beam lock comprises a downhold and a pivotally connected latch, the downhold 1, made as a heavy bar, being slightly arched longitudinally and recessed on its underside at 2 to embrace loosely the beam journal B², the rounded ends 3, 4 of the downhold being shaped to fit in and seat upon the inner bearing A³ and the seat C' of the temporary support.

Referring to Fig. 1 the downhold is shown in operative position by full lines, and it will be seen that its flat under face 100 between the end 3 and the journal recess 2 rests squarely upon the top of the offset A', the overhanging part of the bearing A³ preventing any lifting of the end 3 of said downhold. A locking latch 5, bifurcated at 105 its upper end to present parallel cheeks 6, is pivotally connected at 7 to the downhold between the recess 2 and its outer end 4, the

cheeks embracing the downhold and the temporary support C, said latch terminating in a handle 8 and having at its inner side a transverse shoulder 9 at the lower ends of the cheeks 6. The shoulder 9 is adapted to pass under the clamp portion C², C³ of the support when the latch is in locking position, and referring to Fig. 1 it will be seen that at such time the latch depends practically vertically from the pivot 7, and the latter is directly above the co-operating faces of the shoulder 9, and the clamp, which thus serves as a fixed keeper for the latch. Any lifting or upward movement of the beam acts through its journals to raise the outer ends of the downholds 1, but the latter are kept down and in place by their latches 5, the shoulders 9 at such time extending beneath their keepers, so that the beam journals are held positively in the bearings A². To unlock the beam the weaver grasps the latch handle 8 and swings the latch 5 upward on its pivot 7 into dotted line position, Fig. 1, and thereby unlocks the downhold, and by a still further upward movement of the latch the downhold 1 is swung up into dotted line position, disengaging it from the journal and withdrawing its end 3 from the bearing A³, the recess 2 being made long enough to permit such movement of the downhold. The downhold and latch are now removed bodily and the beam is free to be removed. A reverse operation serves to first position the downhold and then the latch is swung down and its shoulder is brought into locking engagement with the fixed keeper therefor. When the beam lock is in its operative position the weight of the latch keeps it in depending position, with its shoulder in engagement with the keeper, and as any lift of the beam acts with a direct upward pull on the latch there is no necessity for a tight fit or engagement between the latch shoulder and the keeper. It will also be apparent from an inspection of Fig. 1 that while the downhold is arranged to coöperate at its outer end with the usual temporary support for the beam journal the said support is not necessary to the operation of the beam lock, inasmuch as the downhold is positively held at its inner end and rests upon the top

of the beam journal between the latch pivot and the positively held inner end.

Various changes or modifications in details of construction and arrangement may be made by those skilled in the art without departing from the spirit and scope of my invention as set forth in the claims hereunto annexed. 60

Having fully described my invention, what I claim as new and desire to secure by Letters Patent is:

1. In a loom having each of its sides provided with an offset having at its top an open bearing for one of the beam journals and a temporary journal-support, a warp-beam, a downhold recessed between its ends to fit over the beam journal and adapted to seat removably at its inner end in a recess on the top of the offset and at its outer end on the top of the temporary support, a fixed keeper below the support, and a latch pivotally connected with the downhold between its outer end and the journal recess and having a transverse shoulder to extend under the keeper when the latch is depending from the downhold, the coöperation of said shoulder and the keeper acting through the latch to maintain the downhold in locking position. 75

2. In a loom having each of its sides provided with an offset having at its top inner and outer open bearings adapted to receive one of the beam journals, a warp-beam, a downhold recessed between its ends to fit over the journal when seated in the outer bearing, the inner end of the downhold being adapted to enter the inner bearing and seat upon the top of the offset, a latch pivotally connected with the downhold between its outer end and the journal recess and adapted to depend from the downhold when in locking position, a transverse shoulder on the latch, and a fixed keeper on the offset, 95 to be engaged by the shoulder when the latch is in locking position.

In testimony whereof, I have signed my name to this specification, in the presence of two subscribing witnesses.

CARL E. BAILEY.
